UNITED STATES PATENT OFFICE.

CHRISTIAN GIRL, OF CLEVELAND, OHIO, AND THOMAS J. FAY, OF BROOKLYN, NEW YORK, ASSIGNEES, BY MESNE ASSIGNMENTS, TO THE STANDARD PARTS COMPANY, OF CLEVELAND, OHIO, A CORPORATION OF OHIO.

PROCESS AND APPARATUS FOR MAKING SPRINGS.

1,258,762.

Specification of Letters Patent. Patented Mar. 12, 1918.

Application filed July 28, 1913. Serial No. 781,584.

To all whom it may concern:

Be it known that we, (1) CHRISTIAN GIRL, (2) THOMAS J. FAY, citizens of the United States, respectively residing at (1) Cleveland, (2) Brooklyn, in the county of (1) Cuyahoga, (2) Kings, and State of (1) Ohio, (2) New York, have invented a certain new and useful Improvement in Processes and Apparatus for Making Springs, of which the following is a full, clear, and exact description, reference being had to the accompanying drawings.

This invention relates to a process for manufacturing springs and to an apparatus whereby such process may be realized. It is the object of this invention to provide a process whereby the manufacture of springs of the flat-leaf type may be carried on continuously after the plates have been cut to length and such plates as it may be necessary to so treat have been forged to provide the eyes thereon, after which initial preparation the plates are subjected successively to the following steps:—(a) heating to the cambering temperature; (b) cambering; (c) heating to the hardening temperature; (d) quenching, in order to harden; (e) heating to the annealing temperature; (f) cooling, to complete the annealing; (g) finishing.

Further and more limited objects of the invention will appear hereinafter in connection with the detailed description of the process and apparatus disclosed herein.

In carrying out the continuous process, an annular furnace is preferably employed having under the heating chamber a rotary platform or turn-table whereon the spring plates are supported, the furnace being provided with openings of as limited extent as will permit the introduction and withdrawal of the stock, these openings being located respectively at the charging station, the cambering station, and the quenching station. In addition to the rotary platform or conveyor by which the stock is subjected to the different temperature conditions in the furnace, a conveyor is provided for conducting the plates, after having been heated to the annealing temperature and withdrawn from the furnace, to the finishing apparatus, which preferably comprises a sand blast machine.

In the drawings forming part hereof, Figure 1 represents a somewhat diagram-

matic plan view of the apparatus whereby the method is practised; Fig. 2 an enlarged sectional detail of the furnace, the left hand side of the figure illustrating the construction of the heating chamber and the right-hand side illustrating the construction of the turn-table and charging openings; while Figs. 3 and 4 are vertical sectional views corresponding approximately to the lines 3—3 and 4—4 of Fig. 1.

Describing by reference characters the various parts illustrated herein, 1 denotes generally an annular furnace comprising an upper heating section 2 and a lower rotary annular platform or turn-table 3 whereby the articles to be treated are supported. The furnace illustrated herein is of the electrical type and, within the interior of the annulus defined by the furnace, a number of transformers 4 are indicated, there being one transformer for each section A, B, and C of the furnace. The number of transformers and the number of furnace sections may be varied in accordance with varying conditions of use. The furnace is constructed of material ordinarily employed for this purpose and is preferably provided with air spaces 5 within the side and top walls thereof, for the purpose of minimizing heat losses. At suitable intervals, plugs 6 are provided having air spaces 7 therein, said plugs serving to close the charging openings through which resistance material 8, preferably in the form of fine coke, may be introduced. The charges of resistance material are supported on a fire-brick arch 9.

Each section will be provided with two or more electrodes 10 which may be conveniently inserted through the inner wall of the furnace, in such numbers and at such distances apart as may be necessary in order to secure the proper distribution of the electric current through the resistance formed by the carbon as will produce the desired temperature.

The outer cylindrical wall of the furnace is provided with three openings 11, 12 and 13. These openings are of a minimum vertical and lateral extent to permit the easy insertion and removal of the stock therethrough. Above each opening, the fire-brick wall 9 is arched upwardly and outwardly, as shown at 9^a, to facilitate the charging and discharging operations. Op-

posite the opening 12, a cambering machine is provided, this cambering machine being indicated conventionally at D. No particular construction of cambering machine is shown herein, it being sufficient for the purposes of the invention that a machine of standard construction be employed.

Beneath the heating chamber 2 of the furnace and beneath the fire-brick arch 9 which defines the bottom of said chamber, there is located the rotary annular platform or turn-table 3. This rotary platform may be a continuous annular truck, supported by wheels 14 on a circular track 15, or the platform may be composed of a plurality of trucks connected together. The platform will be composed largely of heat-resistant material, such as fire brick, and this material forms a support for the plates during the heating operations. For the purpose of driving the platform, a motor 16 is shown, the motor having a shaft 17 driving a shaft 18 through any suitable gearing, a worm 19 and worm gear 20 being illustrated. The shaft 18 projects through the inner cylindrical wall of the furnace and is provided with a gear 21 meshing with a rack 22 on the underside of the platform, whereby the platform or turn-table is rotated at a speed requisite to secure the necessary heating effect.

Opposite the opening 13 there is provided the quenching bath, indicated at E. This bath comprises an open tank containing the quenching liquid, which is preferably oil. For the purpose of maintaining substantially constant the temperature of this bath, a spray pipe 24 is provided, said pipe being adapted to spray water in a finely divided condition on top of the oil. As the water globules sink through the oil, they are heated to the boiling point by the oil, the latent heat of evaporation of the water serving to keep the temperature of the oil at substantially the boiling point of the water; in fact, owing to the production of a partial vacuum in the minute oil chambers which inclose the water globules, the water boils below atmospheric pressure and at a temperature less than its normal boiling point, thereby reducing, or tending to reduce, the temperature of the oil in the tank E somewhat below the boiling point of water measured under atmospheric pressure. In case any excess water is sprayed through the pipe 24, such excess water can pass through the interstices of a bridge 25 extending across the oil tank, above the bottom thereof, said bridge forming a support for the spring plates 23.

Other methods may be employed for maintaining the temperature of the quenching liquid substantially constant, but the manner herein illustrated and described is believed to be not only efficient but extremely

economical. A further advantage from an efficiency standpoint, in the foregoing method of cooling the oil, resides in the fact that the passage through the oil of the steam generated from the water globules creates a condition of turbulence in the oil whereby spheroidal action between the quenching oil and the heated plates is defeated, with the result that the plates are quenched more quickly and efficiently. In the quenching process, it is particularly desirable to obtain a rapid quenching of the steel, since this rapid quenching action produces the desired carbid condition in the steel; and the cooling method described is particularly conducive to this result.

Opposite the opening 11 a conveyer 26 is provided, whereon the plates 23 are placed after passing through the annealing section C of the furnace. These plates are carried by the conveyer through a sand blast machine, indicated conventionally at F, comprising a supply pipe 27 for sand and air and a plurality of nozzles 28 projecting into the chamber through which the plates pass. A motor 29 is shown as driving the conveyer 26.

With the parts constructed and arranged as described, the operation will be as follows:—Such of the plates 23 as are required to be given a preliminary forming operation (for instance, main plates) are subjected to the proper operation before being inserted through the opening 11 upon the annular platform 3. This platform is driven in the direction of the arrow on Figs. 1 and 2, and the plates are carried thereby beneath the heating chamber A, the temperature of this chamber and the rate of travel of the platform being so proportioned that, by the time the plates have reached the opening 12, they have received the proper cambering temperature. Preferably the heating chamber or section A and the heating chambers or sections B and C of the furnace are so heated that a progressively increasing temperature is obtained therein from the inlet to the outlet end of each section. As the plates arrive at the opening 12, the operator removes them and cambers them in the machine D, replacing the cambered plates upon the turn table through the opening 12. The plates then pass beneath the heating chamber B, where they are subjected to the hardening temperature. The temperature within the chamber B and the rate of travel of the platform are so adjusted and proportioned that, when the plates arrive at the opening 13, they will have been heated to the desired temperature but without any danger of burning or overheating and without any unnecessary heating, the electric form of furnace being particularly adapted for obtaining these results. On arriving at the

opening 13, the plates are removed and inserted in the quenching bath E. After the quenching operation they are placed upon the rotary platform 3, through the opening 13, and then are conveyed through the annealing section located beneath the heating chamber C. The operator removes the plates through the opening 11 and places them upon the conveyer 26, which is of such length and driven at such speed that, when the plates reach the sand blast apparatus F, they will be completely annealed. In the sand blast apparatus, the sand operates not only to remove the scale and other blemishes, but hastens the cooling of the plates. The annealing benefits having been derived during the travel of the plates to the sand blast apparatus, it will be advantageous to quickly remove the excess heat and thus hasten the production operation through the cooling, as well as cleaning, action of the sand blast. From the sand blast apparatus, the plates are finished, assembled, and tested, in accordance with the ordinary practice.

With the foregoing apparatus and process it is possible to produce springs through a series of continuous operations and to accomplish this result in a manner that will insure the proper heat treatment necessary to secure uniformly high quality in the finished product and to accomplish this result with maximum speed, economy and efficiency.

Having thus described our invention, what we claim is:—

1. In an apparatus of the character set forth, the combination of a series of three spaced heating chambers having means for heating the same respectively to temperatures requisite for cambering, tempering and annealing metal articles, a conveyer extending in operative relation to all of said chambers, means for driving said conveyer, a cambering device between the first and second heating chambers and a quenching device between the second and third heating chambers.

2. In an apparatus of the character described, the combination of a series of three heating chambers, electrical means for heating said chambers respectively to temperatures requisite for cambering, tempering and annealing metal articles, a cambering machine interposed between the first and second chambers, and a quenching device interposed between the second and third chambers.

3. In an apparatus of the character set forth, the combination of an annular series of spaced heating chambers, means for heating the said chambers respectively to temperatures requisite for cambering, tempering and annealing metal articles, conveyer mechanism arranged in operative relation to said chambers, means for driving said

mechanism, a cambering machine interposed between the first and second chambers, and a quenching device interposed between the second and third chambers.

4. In an apparatus of the character specified, the combination of an annular furnace comprising an annular series of spaced heating chambers, means for heating said chambers respectively to temperatures requisite for cambering, tempering and annealing metal articles, a rotary conveyer adjacent to said heating chambers, one of the walls of the furnace being provided with charging and discharging slits between the heating chambers, a cambering machine opposite the first slit, a quenching device opposite the second slit, a conveyer opposite the third slit, and a sand blast apparatus co-operating with the articles carried by the last mentioned conveyer.

5. In an apparatus of the character specified, the combination of an annular furnace comprising an inner cylindrical wall and an outer cylindrical wall and comprising an annular series of spaced heating chambers in the upper portion of the furnace, a rotary conveyer beneath said heating chambers, the outer wall being provided with charging and discharging slits between the heating chambers, a cambering machine opposite the first slit, a quenching device opposite the second slit, a conveyer opposite the third slit, and a sand blast apparatus co-operating with the last mentioned conveyer.

6. In an apparatus of the character set forth, the combination of a series of heating chambers arranged and equipped for heating material to cambering, hardening, and annealing temperatures, a conveyer extending in operative relation to said chambers, a sand blast apparatus, and a conveyer extending from the third chamber to the sand blast apparatus and arranged to convey articles from the last chamber of the series in operative relation to such sand-blast apparatus.

7. In an apparatus of the character set forth, the combination of an annular series of spaced segmental heating chambers, a rotary turn table arranged beneath said chambers, means for heating said chambers to different temperatures corresponding to the heat treatment to which the articles on said turn table are to be subjected, and means interposed between said chambers for the treatment of the metal heated within such chambers.

8. In an apparatus of the character set forth, the combination of an annular series of spaced heating chambers, a rotary turn table arranged beneath said chambers, curved transforming devices within the annulus defined by said chambers, electric heating means for each chamber supplied from said transformers, and adapted to heat said

chambers respectively to temperatures requisite for cambering, tempering and annealing metal articles on said turn table, means for driving said turn table, and means oper-
5 tively interposed between the chambers for treating the metal heated therein.

In testimony whereof, we hereunto affix

our signatures in the presence of two wit-
nesses.
